W. P. STUBBS

COLLAPSIBLE STAND

Filed Aug. 31, 1921

11 23 INVENTOR
WILLIAM P. STUBBS,
BY Bright & Bailey ATTORNEYS

UNITED STATES PATENT OFFICE.

WILLIAM POWNALL STUBBS, OF LEEK, ENGLAND.

COLLAPSIBLE STAND.

Application filed August 31, 1921. Serial No. 497,289.

To all whom it may concern:

Be it known that I, WILLIAM POWNALL STUBBS, subject of the King of Great Britain, residing at 42 Osborne Street, Leek, Staffordshire, England, have invented new and useful Collapsible Stands (for which I have filed application in Great Britain, No. 13,937, May 20, 1920); and I do hereby declare the following to be a full, clear, and exact description of the invention, such as will enable others skilled in the art to which it appertains to make and use the same.

This invention relates to collapsible stands, for supporting or displaying calendars, menu cards, advertisements, wearing apparel and other suitable articles, of the kind constructed for preference from a single piece of material bent to form two thicknesses of material the opposing faces of which are secured together over a pre-determined area the lower end being unattached and formed with a number of bending creases or their equivalent so disposed as to enable the bottom edges of the adhered or connected surfaces to rest upon the base of such lower end of the stand so as to spread the two thicknesses of material apart at such lower end and thus provide a supporting surface for the stand and means for temporarily maintaining such lower portion in its set up position as above described consisting of a tongue piece formed integral or otherwise with said base portion and adapted to interengage with an adjacent portion of the device for the purpose above mentioned.

Hitherto the base portion of an article of the above character assumed a substantially triangular shape when "set up" and the tongue piece or pieces engaged a slot in the bottom side of such base portion for supporting the same in such set up position.

An article according to the present invention has a base portion which assumes a substantially rectangular form when "set up" and the tongue piece or pieces is or are cut out of the bottom side of such base portion and project vertically upwards so as to engage between the opposing faces of the upper portion of the device.

The present invention therefore comprises a collapsible stand of the above character having a body portion formed by securing the opposing faces of the two thicknesses of material together over a predetermined area or series of points and bounded along its bot-

tom edge by parallel bending creases formed one in each thickness of material and close up to the connected surfaces, a base portion consisting of an area over which the thickness of material are unattached and when collapsed up flat bounded upon one longitudinal side by the aforesaid bending creases and on the other longitudinal side by the bottom edge of the thicknesses of material and having a pair of spaced parallel bending creases formed in each thickness of material substantially midway between the said boundary sides of the base portion so as to cause the sides of the base portion, when set up, to spread out and form a substantially rectangular figure.

In order that the invention may be clearly understood several practical applications of the same will now be described by aid of the accompanying drawings in which:

Fig. 1 is a plan of one form of stand according to this invention showing the same collapsed.

Fig. 2 is a perspective view of the same in the open or "set up" position and to a larger scale.

Fig. 3 is a plan of a further form of stand according to this invention showing the same collapsed.

Fig. 4 is a perspective view of the same "set up."

Fig. 5 is a plan of a further form of stand showing the same collapsed.

Fig. 6 is a perspective view of the same "set up."

Referring now to Figs. 1 and 2 the stand therein illustrated is constructed from a single piece of cardboard or similar material with the exception of two attached pieces hereafter to be described. The material is bent double about the top edge or bending crease 10 and from a convenient distance down the two thicknesses of material 11 and 12 are secured together face to face by staples 13 or other suitable fastening means or by gluing so as to constitute a rigid and normally vertical portion 14 which portion is bounded at top and bottom by horizontally disposed bending creases 15 and 16 respectively which are arranged in pairs in each thickness of material 11 and 12.

A further pair of bending creases 17 are disposed parallel with and mid-way between the bending creases 10 and 15 by which means the upper portion, which will be gen-

erally referred to hereafter as 18, may be collapsed towards the top edge of the portion 14 for the purpose of providing an automatically adjustable gripping medium for securing articles in position therein such articles being inserted through the cut away portion 19 so as to extend inwardly in one or both directions. When the article is positioned the top portion 18 is released when 10 it will automatically bend to assume an elongated or trapezoid shape as shown in Fig. 2, thus effectively closing in upon and gripping the enclosed portions of the article to be supported.

15 The two extremities of the thicknesses 11 and 12 are lapped over as shown and secured together by staples or other fixing means which are not shown. The lower portion thus constituted and bounded on one side 20 by the bending crease 16 and on the other by the bottom edge is referred to generally by the reference numeral 21. This portion 21 is adapted to constitute the base of the stand and for this purpose it is provided 25 with suitably spaced parallel bending creases 22 and 23 arranged in pairs as are the other and before mentioned bending creases. These creases 22 and 23 and the creases 16 enable the portion 21 to be collapsed up against the bottom edge of the portion 14 the normal position being reached when the inside face of the adjacent end of the thicknesses 11 contacts with the bottom edge of the portion 14.

30 35 In this position the top faces 24 of the portion 21 are inclined inwardly towards the sides of the portion 14 thus providing convenient ledges or receptacles for holding pens, pencils and analogous articles. When 40 only partially collapsed the sides of the portion 21 form an approximately rectangular figure.

The portion 21 is maintained in the supporting position illustrated in Fig. 2 by 45 means of a pair of tongue pieces 25 which are integral with the thickness 11 from which they are severed on two sides only the remaining or attached side constituting the bending crease about which such tongue 50 pieces may be bent so as to assume a position which is normally at right angles to the surface to which they are attached. This bent or vertical position is indicated in Fig. 2 where the tongue pieces are shown 55 as inserted between the thicknesses 11 and 12 composing the portion 14. The frictional grip thereby obtained between these inserted tongue pieces and the inside opposing faces of the thicknesses 11 and 12 is 60 sufficient to maintain the base portion 21 in the collapsed or supporting position shown. Buttresses 26 are provided arranged one upon each side of the portion 14 for supporting the same in the upright position 65 such buttresses being formed integral at

their top with such portion 14 by cutting along the remaining sides in the usual manner. The lower ends of these buttresses are enlarged as shown and indicated at 27 whilst the corresponding portions of the recess 28 in each of the surfaces 24 are similarly enlarged or widened consequent upon such buttresses having been removed therefrom by cutting as previously explained. The recesses 28 are thus dovetail in shape the widest end being adjacent to the outer edges of the surfaces 24 and constituted by the bending creases 22.

To support the portion 14 the buttresses are bent inwardly as shown the enlarged ends or inturned extremities 27 being then inserted through the wide ends of the recesses 28 and finally pushed up so as to reside beneath the over lapping edges of the surfaces 24 as indicated in dotted lines in Fig. 2. In this position they are supported against the undersurface of such over lapping edges by separate strips 29 which are secured by their outer edges directly beneath each of the recesses 28 so as to constitute with the over lapping edges of the surfaces 24 grooves for receiving the corresponding edges of the inturned extremities 27 of the buttresses, and operating to support such inturned extremities flat against the undersurface of the surfaces 24.

In Figs. 3 and 4 is illustrated an embodiment of this invention as adapted for carrying or supporting menu cards, calendars and analogous flat articles. In this example the two thicknesses of material 11 and 12 are bent double about a longitudinal bending crease 30 which constitutes the centres of the base portion 21. The bending creases 22, 23, and 16 in this base portion 105 are situated and operate as described in connection with Figs. 1 and 2.

The two thicknesses 11 and 12 are glued together to constitute the portion 14 a predetermined area being left unattached for the reception therebetween of the tongue piece 25. The menu card, calendar or other flat article is attached to either or both faces of the portion 14. The nose of the tongue piece 25 is shown as protected by a metal shield 31. Such a shield may with advantage be used in every embodiment of the invention as it effectually prevents the tongue pieces from becoming frayed or split after constant use. The embodiment illustrated in Figs. 5 and 6 is adapted especially as a stand for displaying collars and similar articles for which purpose the top edges of the thicknesses 11 and 12 are cut at an angle and unattached down to the bending creases 32 which bending creases enable such edges to be splayed apart as shown in Fig. 6. The articles to be displayed are attached between these edges in any convenient and suitable manner. To enable such edges to 110 115 120 125 130

be bent in various directions the same may be split as indicated at 33. The bottom or supporting portion 21 is as illustrated and described in connection with Figs. 3 and 4.

5 Having now particularly described and ascertained the nature of my said invention and in what manner the same is to be performed, I declare that what I claim is:—

10 A collapsible stand formed from a single sheet of material having a line of fold dividing the sheet into a body portion and a supporting base, said sheet being adapted to be folded to extend the base laterally outward with respect to said body portion, said

15 body portion and said base being provided

with slits extending across said line of fold to provide a buttress having a free end, the slits in the base portion being diverged relatively and the free end of the buttress being correspondingly formed and adapted 20 for insertion into the space in the base formed by said diverging slits when the base portion is extended laterally with respect to the body portion thereby to provide an interlock between the base portion and said 25 buttress.

In witness whereof I have signed this specification.

WILLIAM POWNALL STUBBS.
